CLAIM

The ornamental design for an automatic cash dispenser, as shown and described.

DESCRIPTION

FIG. 1 is a perspective view of an automatic cash dispenser showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines show portions of the article not claimed and forms no part of the claimed design.

1 Claim, 7 Drawing Sheets
